UNITED STATES PATENT OFFICE.

CHARLES ALMON JACKSON, OF LAWRENCE, MASSACHUSETTS, ASSIGNOR TO
DAVID F. ROBINSON, OF SAME PLACE.

TELEPHONE SYSTEM.

SPECIFICATION forming part of Letters Patent No. 308,165, dated November 18, 1884.

Application filed November 28, 1883. (No model.)

To all whom it may concern:

Be it known that I, CHARLES ALMON JACKSON, a citizen of the United States, residing at Lawrence, in the county of Essex and State 5 of Massachusetts, have invented certain new and useful Improvements in Telephone Systems; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to telephonic circuits whereby the time now consumed in waiting for an opportunity to call up any given subscriber is economized and the necessity of a "central office," so called, is avoided.

20 The invention is an improvement upon or extension of a system shown and described in application for a patent filed by myself on the 17th day of September, 1883, in which I discard the central office, as before stated, and 25 in lieu of the ordinary circuits having their termini massed in such office, I employ a number of closed circuits sufficient to enable any subscriber under ordinary circumstances to find some one of them unoccupied, or to greatly 30 multiply the chances of his thus finding one, and I run the entire series of these wires through each subscriber's instrument, and in which, moreover, I furnish to each subscriber an adjustable or movable switch-board carrying a wire in which is included a receiver and 35 transmitter, and whose ends are connected with conductors secured to such switch-board, these conductors being so arranged as to close the circuit through the wire when the line is 40 broken, thereby enabling any subscriber to put himself in communication with and operate over any circuit-wire.

The objects of my present improvements are, 45 first, to enable a subscriber on any one telephonic circuit to communicate directly with any subscriber upon any line with which his instrument connects—for instance, in a different city; secondly, to enable two or more subscribers whose lines run through the switch- 50 board to communicate with two or more other subscribers from their own instrument at the

same time without conflicting with each other; thirdly, to combine in one instrument means for enabling these two objects to be carried out, and also for carrying out the invention 55 herein first premised—that is, to enable any subscriber to put himself or his instrument directly in communication with a subscriber on any other line of the system.

The drawings accompanying this specification represent in Figure 1 a plan, and in Fig. 2 a cross-section, of a device containing my invention. Fig. 3 is a bottom view of the switch-board. Figs. 4 and 5 represent plans of the registering or calling mechanism in different subscribers' offices, showing the secondary circuit to enable a certain subscriber to be called, and further the main current through said machine both for calling and establishing a circuit for talking. Fig. 6 is a front 70 view of the dial-plate. Fig. 7 is a front perspective view of the indicating devices; Fig. 8, a rear perspective view of the registering mechanism; Fig. 9 is a diagram of the entire system.

In said drawings, A is a tablet, upon the top of which are placed a number of keys, B B B, &c., arranged in a straight row and parallel to each other, the number of these keys being determined by the extent of business carried 80 on in any particular locality or localities. In the present instance I have shown eight keys, each of which is composed of two plate-springs, a b, of conducting metal, the free end of one (for instance, a) resting upon the free end of 85 the other, b, as shown in Figs. 1 and 2.

C C C, &c., represents a series of telephonic circuit-wires, each operated by a battery and connected with a return wire or wires, D²⁰, thereby closing the circuit by the 90 insertion of plugs connected with the latter wire into ports upon the main lines C C C, &c. each wire being intercepted by a key, B, as shown. Where the two portions a b of a key are separated, the circuit through the wire C 95 is broken, and vice versa.

D represents a switch-board disposed above the range of keys B B, &c., and supported upon horizontal parallel rods E E in manner to slide upon the latter transversely of the 100 said range of keys, said switch-board preferably carrying a pointer, F, to enable it to be

readily adjusted in position over any given key. The switch-board D is composed of hard rubber or other material adapted to insulate it from its supporting-rod E E.

- 5 G in the drawings represents a wire, the two ends, c d, of which pass down through the switch-board, the end c being connected to a contact-point or conductor, f, in the form of a knob secured to and depending from the under side of said switch-board. The end d of the wire G connects with a contact-point, d', extending upward through the switch-board. Included in the wire G are a receiver, H, and transmitter I.
- 5 e in the drawings represents a second contact-point in the form of a knob carried by and depending from the under side of the switch-board D, this rod being connected by a conducting metal plate, j, with a second contact-point, k, extending through the switch-board. The two knobs e f are so arranged to the keys B B, &c.—that is, one below the other—as, when passing over any one of said keys, to separate the two parts of the latter 25 and break the circuit through the wire C direct and re-establish such circuit through the wire G, thereby putting the receiver and transmitter contained in such wire in communication through such wire C.
- 30 As shown in the accompanying drawings, the knob f extends below the knob e, and operates and serves to depress the lower leaf, b, of any key, while the knob e operates with the upper leaf, a, of any key. When the switch-board is moved over any one key, the knob e bears upon and establishes communication with the upper portion, a, of said key, while the knob f bears upon and establishes communication with the lower portion, b, of such key, at the same time separating the two leaves by pushing down b, and thereby breaking the circuit through such key.
- 35 P represents a vibratory arm, of conducting metal, pivoted at its base to the contact-point d. The free end of the arm P is adapted to be swung into contact with the point k, or a point, K, to be explained.
- 40 J in the drawings represents a wire, one end of which is connected with a third contact-point or conductor, K, secured to the top of the switch-board, the opposite end of this wire carrying, for convenience in use, a plug adapted to be inserted in a socket, i, in the top of either screw-post M, which is connected 45 with one end of each key B.
- 45 To more fully describe the operation of this switch-board and the system connected therewith, I will suppose the board D' (see Figs. 1 and 2) resting with its pointer F upon the key b, while the key P is upon the contact-point k. The current is along leaf a to knob e, to button k, along key P, contact-point d', and from the point d to the wire G, through the transmitter H and receiver I to the point c and knob f, to the leaf b, corresponding to the leaf a, and out upon the line c, the situation of the knobs e and f being such that the normal

direct current is broken by the separation of the two leaves a b and the current diverted through the switch-board D and transmitter 70 and receiver connected therewith out upon the same line, the object to be accomplished being simply to enable the person holding the receiver to his ear to find whether the line is occupied without disturbing the conversation 75 or current on that line. If he finds this line C occupied, he shifts his board to another line, still maintaining the key P upon the contact-point k. Now, on the other hand, suppose the figure 1 represents a switch-board of a subscriber in London, and he desires to talk with some one on his system in Liverpool, he slides his instrument along, holding the receiver to his ear, until he reaches M²³ and finds line C²³ unoccupied. He at once inserts plug L²⁴ into 80 M²³. The current along C²³ being as yet uninterrupted, he continues moving his board D until he finds a line, C²⁴, unoccupied, when, in order to hold this latter line, he moves the key P to K, when the normal current along wire 90 C²⁴ is broken and a cross-current is established from line C²³ to line C²⁴, which leads to Liverpool. Considering the currents on line C C, &c., as positive, the current on line D²⁰ is negative; hence to close a circuit, Liverpool inserts plug 27 in port 26 on wire C²⁴, and London inserts plug 24 into port 25 on wire C²³. 95

By referring to Figs. 1 and 2 the current can be more clearly and easily followed. From the port M²³, plug L²⁴ inserted therein, it follows the wire J to contact-point K, thence along the key P to contact-point d', to wire C, which emerges from the rubber plate of the board at d, and through the transmitter H and receiver I to the point c, to the knob f and leaf b, to the wire C²⁴, to Liverpool, passing through the latter's transmitter and receiver port 26 and plug 27, along the wire D²⁰ to and returns by plug 24 and port 25 to C²³. When these two subscribers are through talking, 110 plugs 24 and 27 are removed, the key P thrown back to k, which permits both currents on wires C²³ and C²⁴ to become direct ones, the current on wire C²⁴ passing through the transmitter H and receiver I so long as the pointer 115 F rests over said wire, but otherwise being undisturbed. By this simple device, when a subscriber desires to communicate with another, he has only to place the arm P in contact with the point k and move the switch from 120 one key to another, thereby for the time switching the circuit on some one line C through his receiver H, which he holds to his ear, and is thus enabled to ascertain which wire C is unoccupied. When an unoccupied 125 wire, C, is found, the subscriber allows the switch-board to remain over such key, and can then communicate directly with any subscriber on said line through the transmitter H. As soon as the knobs e f pass by and release the 130 leaves a b, composing the key, the leaves automatically close and the circuit is re-established direct through the wire C.

I have described my invention as applied to

a telephonic system which necessitates the discarding of a central office and the employment of additional circuit-wires. The principle of my invention, however, is applicable to the present system, in which a central office is used, as it will be only necessary in this latter system to mass the wires together at each subscriber's instrument in the manner shown in the drawings, in which the wires 10 C C, &c., may be the wires of the present system.

In connection with the above improvements in the operation of telephonic circuits, I employ an instrument carrying a dial which contains the numbers of all the subscribers on a given circuit or number of circuits, and an index hand or pointer operating therewith capable of being set to any of said numbers, and when so set of opening communication 20 with the subscriber designated by said number. The construction of this device is as follows:

A represents a tablet, upon the top of which is arranged an ordinary electric key, A⁴, and 25 four screw-cups, B³ C³ D³ E³. The bridge of the key is shown at F³, and the contact-point of such bridge at G³. A spring, J³, is secured at its base to the top of the tablet, the free end of this spring bearing upon the periphery of a toothed wheel, K³, of conducting metal secured to a horizontal shaft, L³, supported in bearings in upright standards N³ N⁴, 30 erected upon a base-plate, O³, secured to the tablet, such standards being properly bound together, and, like the base-plate, being composed of conducting metal.

P³ represents a scape-wheel fixed to the shaft L³ alongside the wheel K³, and with the periphery of this wheel operates an escapement, Q³, formed upon one end of a horizontal escapement-lever, R³, such lever being pivoted to a post, S³, erected upon the base-plate O³, and its tail being lifted by a spring, T³, connected with a post, U³, erected above the 45 lever.

V³ represents a horizontal armature secured to the tail of the lever R³, such armature operating with a pair of electro-magnets, W³ X³, supported upon the base-plate O³. The battery for operating this instrument is shown in 50 Fig. 4 of the drawings at Y³. Its negative pole (see Figs. 4 and 6) connects with the screw-cup B³, and this cup connects with the key A⁴ by a wire, Z³. The contact-point G³ of the key-bridge F³ connects by a wire, a², with magnets W³ X³. The magnet X³ is connected by a wire, b², with the spring J³, before 55 named. The standard N³ is connected by a wire, c², with the screw-cup C³, and the screw-post C³ connects with the corresponding post, B³, on the machine of the next adjoining subscriber on this circuit, and the course of the current through each machine is the same as above described until it reaches the last subscriber 60 on this circuit, where it may be grounded by the wire P. The current from the bat-

tery Y³ is continuous, except when one subscriber calls another, in which case this current is broken at the point G³, Fig. 4, by the depression of the key A⁴. The screw-post D³ 70 connects by a wire, g², with a spring, h², secured at its base to the inside of the standard N³, and insulated from such standard by a washer, i². The free end of the spring h² operates with a contact point or pin, j², carried 75 by a circular disk, k², of insulating material, secured to and rotating with the shaft L³, before named. An additional spring, l², is secured at its base to the standard N⁴, this spring being situated on the side of the disk k² opposite its mate h², and, like the latter, operates 80 with the contact-point j² of such disk.

C⁴ in the drawings represents a dial-plate secured to the outside of the standard N⁴, the front end of the shaft L³ extending through 85 this dial-plate and carrying an index pointer or hand, D⁴, to read the scale F⁴ of divisions upon the face of the dial-plate. This scale is an annular one, extending about the plate near its circumference, such scale consisting of 90 a number of equidistant divisions, each of which is numbered and represents a different subscriber. The dials of every subscriber's instrument are alike, and the hands of all the instruments point to the same division upon 95 the scale, and are constantly in rotation, except when stopped and the current broken by the depression of the spring A⁴ when a call is made; but the contact-point of the disk varies with each subscriber, and is so adjusted that 100 when the hand of any instrument is set to any given subscriber's number the contact-point corresponding to his number is embraced by the free ends of the spring h² l². The two circuits are as follows: One, when key A⁴ is 105 raised and in contact with the contact-point G³, is from the negative pole of the battery to post B³, thence by wire Z³ to key A⁴, thence to bridge F³ through contact-point G³, from the bridge by wire a² to magnets W³ X³, from X³ 110 by wire b² to spring J³, from spring J³ through scape-wheel P³ to the shaft L³ of such wheel, thence to standard N³, and from such standard by wire c² to screw-post C³, and from the latter to the next subscriber's post B³, until 115 finally grounded. When this circuit is closed, the hands are in constant rotation, as before stated, over the disk. When the key is depressed into contact with the point H³, the above circuit is broken and the hand stops, 120 and the current from a second battery, 39, enters from the wires upon which are located the transmitter and receiver of the various subscribers—namely, C C, Fig. 1, or D³⁰ on the diagram—through the wire d³, (see Fig. 4,) 125 through the individual machine then in circuit, as follows: From the wire d³ it enters post E³, to standard N⁴, spring l², through the conducting-point, hereinafter to be described, on the wheel k², thence through h² to i², wire 130 g², post H³, wire e, to the bell f², which it operates, and thence passes along one of the

wires C C upon the system, as shown in the diagram, by wire D²⁰ to the battery 39. The current from the battery Y³ is continuous when the key A⁴ is in its normal position—in contact with the point G³. The pointer is rotated as follows, it being observed that the free end of the spring J³ bears upon the point of but one of the teeth of the wheel K³, and the armature V³ being raised by its spring T³; hence the armature V³ is attracted and lowered, and the escapement advances the scape-wheel P³ and the shaft L³ a distance corresponding to one tooth of such wheel, thereby carrying the tooth which is in contact with the spring J³ past the latter and breaking the circuit. The armature is thus released, and is lifted by its spring, thereby advancing the scape-wheel one tooth and bringing into contact with the spring J³ the tooth next succeeding the one last in contact with such spring, which again closes the circuit, as before, and lowers the armature a second time, and these movements are repeated in rapid succession, thereby intermittently opening and closing the circuit and rotating the wheel and shaft.

I will now proceed to describe the operation of the machine and system in signaling to some subscriber in the same circuit, which is as follows—subscriber No. 1, say: Fig. 4 represents the machine in his office, provided with a battery, Y³, which supplies the entire line of subscribers on his circuit. The normal current is from this battery through N, post B³, wire Z³, key A⁴, point G³, wire a², through W³, wire b², spring J³, to the standard N³, to wire c², and thence to the next subscriber, No. 2, where it would enter his machine at the corresponding post, B²; and I have adapted the following system of lettering: B² represents B³ on subscriber No. 2. c² is c³ on No. 3. In other words, the numerator of the fraction represents the same object or letter for that part throughout the system, while the denominator refers to the subscriber to which that special part or portion of the device on that system belongs. From part B³ the current follows the same course as above described, and leaves his machine on the wire corresponding to wire c², say c² of machine No. 2, to No. 3, and so on. If No. 3 is the last subscriber on the line, the current is grounded. The current is normally continuous, as the keys A⁴ A⁴ A⁴ are always in contact with the points G³ G³ G³, and through the corresponding wires, a² a² a², of all the machines, keeping the hands D⁴ D⁴ D⁴ constantly traveling around the dial, except when one of the keys A⁴ is depressed, as shown in Fig. 9, and the circuit broken through the wire a², which stops the current at that point, and consequently each hand on every dial on that system. If No. 1 has pressed his key A⁴ and broken the current when the hand on his dial is opposite or upon numeral 3 of the same, he understands that a circuit will be established through the machine of No. 3 to ring the bell of the latter, provided

he (No. 1) inserts the plug 41 in the socket 40 and subscriber No. 3 inserts his plug 44 in socket 45.

Now I will proceed to Fig. 9 and describe the process when subscriber No. 1 calls up No. 3 and proceeds to establish a circuit for talking. The current emanating from battery Y³ continues on uninterruptedly through the several machines of the various subscribers, as above described, and is finally grounded at the end of the system, in this case connecting these subscribers, who may be several miles apart. No. 1, now desiring to talk with No. 3, depresses the key A⁴ (when the current is broken at that point, as shown) at the moment when the pointer D⁴ on his machine is upon the numeral 3, when he knows that he can obtain a current through the machine of subscriber No. 3 in order to call or ring his bell, as I have previously described. The current on wire D³⁰ emanates from the battery 39 and returns to the negative pole of said battery by the wire D²⁰, and each subscriber is connected with that wire or some other which may lead from his office to these subscribers. When No. 1 has broken the current upon wire D¹⁰, he knows the current along wire D³⁰ will pass from this wire along d³. The course of the current through the machine of No. 3 is more clearly shown in Fig. 4, to which the following description refers. From d³ it enters the post E³ to the button connecting with standard N⁴, passes through the spring l², through the conducting-point on the wheel, thence through h² to i², wire g², post D², wire e², to the bell f², which it operates, and thence passes along the wire D²⁰ to the battery 39. When No. 1 has allowed a short time to elapse, sufficient to ring the bell and call No. 3, he inserts the plug 41 into the post 40, and likewise No. 3 hearing his bell ring likewise inserts the plug 44 into post 45. No. 1, as soon as he inserts his plug 41, releases the spring A⁴, when the circuit D¹⁰ is re-established and the current from D³⁰ through the machine of No. 3 is broken. A complete circuit is established, as shown by the double dotted lines, from the receiver I and transmitter H of No. 1 through connections 40 41, along D³⁰, by and through connections 44 and 45 of No. 3, and his transmitter H³ and receiver I³, and returns along D²⁰ to No. 1. Upon No. 1 releasing the spring A⁴ the current from battery Y³ is restored, and the dial-hands at once begin moving, which action then permits of No. 2 or some other subscriber, if there are more than three, ringing up some other subscriber.

The switch-board, as shown in Fig. 1 of the drawings, is to be used in connection with wires similar to those shown in Fig. 9 at D³⁰ D²⁰. In other words, C C C represent similar wires, and each wire connecting with three, five, or more subscribers, and there may be fifteen or twenty wires running through each subscriber's individual switch-board. In the present example (see Fig. 1) there are eight

such wires. The object of this board is as follows with reference to Fig. 9: Imagine No. 1 to have rung up No. 3 and is talking with him. The switch-board in Fig. 1 is in the office of 5 No. 2. The latter, not knowing wires D³⁰ and D²⁰ are in use, tries to ring up No. 5 in the same system, but finds the wires occupied, and receives no reply, as said wires are short-circuited by and through the connections 40 41 10 44 45 of subscribers No. 1 and No. 3. He shifts his board to another set of wires which are similarly connected to those shown in Fig. 9, and it will be readily understood that occupation of lines D²⁰ D³⁰ by Nos. 1 and 3 will not 15 prevent another subscriber on that line from ringing up any other subscriber, but they cannot talk on the line occupied by Nos. 1 and 3, but must find some unoccupied wire, and it is for quickness and ease in shifting from one 20 line to another that this switch-board is used, thereby dispensing with the central office.

The more fully to explain the operation of my system and the manner of calling up any given subscriber, I have shown in Fig. 9 of the 25 drawings a diagram in which I have grouped a series of dials and pointers and their connections. In this diagram I have used letters of reference with regard to their use on the other figures of the drawings.

30 I claim—

1. In combination, a series of telephonic closed-circuit wires massed together, each including a circuit-breaking key, a movable switch-board adapted to move from one to the 35 other of such keys, a conducting-wire with its opposite ends secured to conductors carried by said board, which conductors operate to open the key and break the circuit thereat, and a receiver and transmitter included in the 40 latter wire, and the combination, with said switch-board, of a plug and wire, substantially as described, for connecting it with the circuit-wire to be called upon.

2. In combination, a series of telephonic

closed-circuit wires massed together, each including a circuit-breaking key, a movable switch-board adapted to move one or the other of such keys, a conducting-wire with its opposite ends secured to conductors carried by said board, which conductors operate to open the key and break the circuit thereat, and a receiver and transmitter connected with the circuit-wires and carried by the switch-board, and a plug and wire, substantially as described, for connecting it with the circuit-wire to be 45 called upon, and a suitable device for indicating the subscriber thus called.

3. In combination with the wires C C, &c., keys B B, &c., switch-board D, its wire G, receiver H, transmitter I, with one end of the 50 wire G connecting with the knob f, and the other with the contact-point d', and the wire J, with its conducting-knob K, and connected with a contact-point carried by the switch-board.

4. The combination of the wires C, keys B B, and switch-board D with the contact-points K and k, carried by said board, the central contact-point, d', the arm P, pivoted on said central contact-point and arranged to 55 make contact at will with either point K or k, the knobs e and f, attached to the under side of said arm and adapted to come into contact with the two parts of a key and separate them from one another, and the wires e and G, connected to the instruments H and I, as stated, the various devices being electrically connected, as described, in order that the moving of arm P from one position to another 60 may break one circuit and open another, substantially as set forth.

In testimony whereof I affix my signature in presence of two witnesses.

CHARLES ALMON JACKSON.
